BOTTLE CAP RECEIVER

Filed Aug. 30, 1926

2 Sheets-Sheet 2

UNITED STATES PATENT OFFICE.

JOHN HENRY McDONALD, OF HAMBERG, NORTH DAKOTA.

BOTTLE-CAP RECEIVER.

Application filed August 30, 1926. Serial No. 132,531.

This invention has for its object to provide a receiver for bottle closures as said closures are pulled from the bottles by a removing device so that the closures will be prevented 5 from falling upon the floor or a table.

Another object of the invention is to provide means whereby the receiver can be easily and quickly detached from its supporting means so that it can be emptied of the 10 closures.

This invention also consists in certain other features of construction and in the combination and arrangement of the several parts, to be hereinafter fully described, illustrated in 15 the accompanying drawings and specifically pointed out in the appended claims.

In describing my invention in detail, reference will be had to the accompanying drawings wherein like characters denote like or 20 corresponding parts throughout the several views, and in which:—

Figure 1 is a front view of the device.

Figure 2 is an edge view with parts broken away.

Figure 3 is a similar view, with the top part of the receiver pushed inwardly.

Figure 4 is a view showing a modification.

Figure 5 is a view of another modification.

In these views, 1 indicates a block upon 30 which the cap remover 2 and the receiver 3 are placed. The receiver 3 is of box shape, with its rear piece 4 having a lower depending part 4' and its upper part extended so that it will pass under the front portion of

35 the device 2. A strip 5 is fastened to the lower end of the block 1 with its outer edge turned upwardly to form a space between itself and the block to receive the part 4'. A lug 6 is fastened to each side of the receiver 40 and has a notch 7 therein for receiving a screw 7' or the like projecting from the edge of the block. These lugs and the projecting ends of the bottom piece provide means for detachably holding the receiver to the block.

45 By sliding the receiver upwardly, the lugs and the part 4' can be released from the holding members and the device removed from the block so that it can be emptied. The top part 8 of the box is connected by the hinges 50 9 to the lower part and springs 10 hold the hinge part away from the block. A link 11 which is pivoted at its upper end to the upper part of the box and has a slot 12 in its lower part engaging a projection 13 on the lower

part of the box, limits the movement of the 55 hinge part.

The form shown in Figure 4 is intended to be used with the cup-shaped remover shown at 2'. In this case, the upper end of the bottom plate and the front end of the hinge part 60 8', are each recessed, as at 14.

The form shown in Figure 5, comprises a base 1' to which the removing device 2'' is secured, the lower end of the base having a hook 15 at its lower end. The box-like receiver 3'' has a lip at each end, the upper lip being placed under the device 2'' and the lower one being placed in engagement with the hook 15. An opening 16 is formed in the front of the receiver at the top thereof and an inwardly opening door 17 is hingedly connected with the lower wall of the opening by the spring hinge 18. Thus when a closure is to be removed from a bottle, the neck of the bottle is pushed against the door which gives under 70 the pressure thereof so that the closure can be placed in engagement with the device 2''. As the bottle is being removed, the door swings 75 shut so that the closure is dropped into the receiver. This receiver can be removed from the base by simply raising it to free the lower lip from the hook 15 when the receiver can be removed from the base. This form is 80 much simpler than the first forms of the invention.

85 From the foregoing, it will be seen that when the closure of a bottle is to be removed, the neck of the bottle is pressed against the hinge part 8 and said part is pushed inwardly until the closure of the bottle can be placed in contact with the removing device 2 or 2'. Then the bottle is manipulated in the usual manner to remove the closure and as the bottle is withdrawn, the part 8 will move outwardly and the cap or closure will drop 90 into the same and pass into the lower part of the receiver. The receiver will also catch any liquids that may flow from the bottle when the same is being opened. After the receiver has been filled with the closures, it can be easily removed from the block and emptied and then replaced. The block is 95 adapted to be secured to any suitable support by screws or the like.

100 It is thought from the foregoing description that the advantages and novel features of my invention will be readily apparent.

I desire it to be understood that I may make

changes in the construction and combination and arrangement of the several parts, provided that such changes fall within the scope of the appended claims.

5. What I claim is:—

1. A receptacle for receiving bottle closures from a remover, comprising a body part and a spring controlled hinge part at the upper end of the body part for permitting a bottle 10 to be engaged with a remover.

2. Means for receiving bottle closures from an opener comprising a support, a receptacle detachably connected with the support and having an opening at the top of the front thereof, a door hingedly connected with the receptacle for closing the opening, said door opening inwardly and a spring for holding the door shut. 15

In testimony whereof I affix my signature.
JOHN HENRY McDONALD.
